UNITED STATES PATENT OFFICE.

HENRY M. ESSELEN, OF BOSTON, MASSACHUSETTS.

SNOW-GUARD.

SPECIFICATION forming part of Letters Patent No. 591,594, dated October 12, 1897.

Application filed May 11, 1896, Serial No. 591,037. (No model.)

To all whom it may concern:

Be it known that I, HENRY M. ESSELEN, of Boston, county of Suffolk, State of Massachusetts, have invented an Improvement in Snow-Guards, of which the following description, in connection with the accompanying drawings, is a specification, like letters and figures on the drawings representing like parts.

10 This invention relates to metallic snow-guards for roofs; and it has for its object the production of a guard which can be readily applied to and secured to a completed roof, either slate or shingles.

15 By my present invention I am enabled to apply snow-guards to a completed roof without disturbing it in the least in a rapid and effective manner, as will more fully appear in the following specification, wherein other 20 novel features of my invention will be described, and particularly pointed out in the claims.

Figures 1 to 4, inclusive, are perspective views of several forms of snow-guard embodying my present invention, the "snow-stop" or loop in Figs. 2 and 4 being broken off to save space. Fig. 5 is a longitudinal sectional view of the guard shown in Fig. 1, taken on the line $x-x$ and showing the guard in place 25 on a roof. Fig. 6 is a transverse section on the line $x'-x'$, Fig. 3, and showing the position of a portion of the shank of the guard when on the roof; and Fig. 7 is a perspective view of a portion of a slate roof with a series 30 of snow-guards in position thereon.

35 I have herein shown the snow-guard as preferably made of a piece of heavy wire, comprising a shank a , Fig. 1, upturned at one end, as at a' , and bent laterally in loop form at a'' to form the snow-stop, which projects above the roof transversely to the shank.

The shank a is flattened in a plane substantially at right angles to the upright portion a' and quite thin to readily slip beneath two 45 courses of overlapping slates or shingles, as s and s' , Figs. 5 and 7; and at its opposite end the shank is shown as provided with a preferably spring prong or projection a'' , extended from its under side.

50 When the shank is forced up between the overlapping courses of slates, the prong is

forced into the cavity a^3 in the shank until it passes beyond the upper edge of the slate s , whereupon it immediately springs out and engages said edge, securely holding the guard 55 from withdrawal.

Two adjacent slates of a course usually lap over the top of the shank to better distribute the strain, and to secure greater rigidity of the snow-stop on its shank I swage the metal 60 at the bend, as at a^4 , widening it in the direction of greatest strain.

In Fig. 2 the shank b is flattened in a vertical plane rearwardly from the loop or snow-stop b' and then broadened laterally at its opposite end, as at b'' , said enlargement or fin having a resilient prong b''^x normally bent down below the plane of the under side of the shank. When such guard is applied, preferably, where heavy or thick slates are used, 70 the shank b is slid in between two adjacent slates of a course until the prong b''^x springs over the upper end of the slate of the course beneath, the fin with the vertically-flattened shank preventing twisting or turning of the 75 guard.

Fig. 4 represents a combination of the constructions shown in Figs. 1 and 2, the shank being laterally flattened at c and provided with a retaining-prong c''^x and flattened in a 80 vertical plane at c' to the loop or snow-stop c^2 .

In both Figs. 2 and 4 the vertical flattening is carried to and around the bend b^4 c^4 , respectively, to increase the rigidity thereat and uphold the loop against strain. 85

The side edges of slates are frequently beveled, as at 3, Fig. 6, and to adapt the snow-guard to such slates I make a portion of the shank triangular in cross-section, as at d' , Figs. 3 and 6, with the apex down to fit into 90 the groove made by two adjacent slates of a course.

The upper end of the shank is laterally flattened, as at d , and provided with a prong d''^x , the flattened portion being depressed to 95 be substantially in alignment with the lower edge of the triangular portion d' .

From the foregoing it will be seen that the thin flattened shanks of the guards can be readily inserted between two courses of slates 100 or shingles and pushed up until the prong engages the upper edge of the slate beneath.

My invention is particularly well adapted for application to slate roofs, as it is very difficult to apply snow-guards to a completed roof of such construction.

5 My invention is not restricted to the precise construction nor shape of guard herein shown, nor to any particular shape or size of wire from which the guards are made, so long as the guard composed of a single piece of wire 10 is adapted to be inserted and held in place between two or more previously-positioned roof members.

Having described my invention, what I claim as new, and desire to secure by Letters 15 Patent, is—

1. A snow-guard composed of a single piece of wire bent to form a shank and an upturned loop or snow-stop, said wire intermediate the shank and loop being of increased diameter 20 in a plane perpendicular to the plane of the roof or other support, and parallel to the direction of movement of the snow thereon, substantially as described.

2. A snow-guard adapted to be inserted between the roof members after the latter have 25 been secured in place, said guard being composed of a single piece of wire bent to present a snow-stop portion, and a holding-shank extended therefrom, said holding-shank being constructed for insertion between two previously-positioned roof members, and provided with a depending centrally-located resilient retaining-prong integral with the said holding-shank, and surrounded by the rigid 30 or unyielding body of the shank, whereby said surrounding rigid body portion presents a leading end for the shank unaffected by the changing positions of the resilient retaining-prong, and therefore presenting at all times 35 a leading end capable of ready insertion between adjacent roof members without binding 40 upon either, substantially as described.

3. A wire snow-guard comprising a shank laterally flattened at one end and provided 45 with a downturned resilient projection, an upturned loop at the other end of and transverse to the shank, the metal between said

shank and loop being swaged to impart greater rigidity and strength thereat in the line of greatest strain, substantially as described. 50

4. A snow-guard comprising a shank laterally flattened at one end and provided with a retaining projection, and upturned at its other end to form a loop or snow-stop transverse to the shank, the latter between said loop and flattened portion being downwardly and inwardly beveled along its sides, substantially as described. 55

5. A snow-guard composed of a single piece 60 of wire bent to present a snow-stop transversely to the direction of movement of the snow and having a shank to rest in the interstice between a plurality of roof members lying substantially in the same plane, said 65 shank being wedge-shaped in cross-section with the apex of the wedge inferiorly located, so that the pressure of the snow against the stop will tend to wedge or seat the shank against the abutting edge or edges of the adjacent roof member or members, substantially as described. 70

6. A snow-guard composed of a single piece of wire adapted to be positioned after the several roof members are in place, said guard 75 consisting of a snow-stop portion and its flattened supporting-shank, the latter being adapted to be inserted between and held entirely beneath two adjacent previously-positioned roof members, while the former extends upwardly between and above said adjacent members, said flattened shank having a resilient retaining-prong integral with and normally projecting beyond the central portion of the under face of said shank, substantially as described. 80

In testimony whereof I have signed my name to this specification in the presence of two subscribing witnesses.

HENRY M. ESSELEN.
